UNITED STATES PATENT OFFICE.

JOSEPH DRORAK, OF ELIZABETH, NEW JERSEY.

HAIR-CRIMPER.

SPECIFICATION forming part of Letters Patent No. 339,087, dated March 30, 1886.

Application filed September 28, 1885. Serial No. 178,361. (No model.)

To all whom it may concern:

Be it known that I, JOSEPH DRORAK, a citizen of the United States, and a resident of Elizabeth, in the county of Union and State of New Jersey, have invented certain new and useful Improvements in Hair-Crimpers, of which the following is a specification.

My invention relates especially to devices employed for crimping the hair, and has for its object the provision of a hair-crimper simple, neat, and durable, and whereby the hair may be crimped in a much shorter time than has heretofore been possible.

To attain the desired end, my invention consists, essentially, in a metal spring body or back provided at each extremity with an arm extending at right angles to the body, one of said arms being provided near its extremity with a shoulder, the other bearing two flattened or partly rounded cross-bars, turning easily thereon in such a manner as to be swung to one side or sprung over the arm at the other extremity of the body, resting upon the shoulder above mentioned, being held in place by the spring of the back, all of which will be hereinafter first fully described, and then pointed out in the claim.

In the drawings, Figure 1 is a side elevation of my improved crimper. Fig. 2 is a side view thereof with the cross-bars swung to one side. Fig. 3 is a cross-sectional view at line xx of Fig. 1; and Fig. 4 is a plan view of the device with the cross-bars turned to the right and left.

Like letters of reference, whenever they occur, indicate corresponding parts in all the figures.

A is the body of the device, made of spring metal, preferably flattened, and bent inward at B.

C and C' are arms extending at right angles to the body, the arm C' being provided near its extremity with a shoulder, D.

E are cross-pieces, preferably made rounding, as shown. These parallel pieces are arranged to press against each other, and are pivoted upon the extremity of arm C, being held against displacement when in position by the spring back B.

When constructed and arranged in accordance with the foregoing description, my improved crimper is used as follows: The pieces E are swung to one side, as in Fig. 2, the extremities of the hair to be crimped are placed therebetween, and twisted therearound, and the parts are sprung into the position shown in Fig. 1.

With my improved crimper but a short time is required for giving the hair the requisite crimp, and the device will be found admirably adapted to the uses and purposes for which it is intended.

Having now fully described my invention, what I claim as new therein, and desire to secure by Letters Patent, is—

As a new article of manufacture, the herein-described hair-crimper, consisting of the spring-back B, having arms C and C' of equal length, the arm C bearing two parallel rounded cross-pieces, E, said pieces being perforated at their free ends and arranged to engage with a projection having a shoulder, D, upon arm C', substantially as shown and described.

Signed at Elizabeth, in the county of Union and State of New Jersey, this 21st day of September, A. D. 1885.

JOSEPH DRORAK.
